UNITED STATES PATENT OFFICE

WILLIAM W. ROBERTSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

NEEDLE MOTION FOR AXMINSTER LOOMS

Application filed March 16, 1931. Serial No. 522,884.

This invention relates to looms for weaving Axminster carpet or other similar fabric in which needles are used for inserting the filling.

My present invention relates to the provision of improved mechanism for transversely inserting and withdrawing the needles with respect to the fabric.

It is an important object of my invention to provide actuating mechanism for a needle motion such that the actuating members have a movement in a closed path and without reversal.

A further object is to provide actuating mechanism for a needle motion in which the needle block or holder is stopped and reversed at its limits of travel with an easy "sine-curve" motion.

An important feature of the invention relates to the provision of a chain or band as a driving element in a needle motion, said band being movable in a closed path and in a single direction.

My invention further relates to arrangements and combinations of parts which will be hereinafter described and more particularly pointed out in the appended claims.

A preferred form of the invention is shown in the drawings, in which

Fig. 1 is a front elevation of my improved needle motion;

Fig. 2 is a sectional end elevation, taken along the line 2—2 in Fig. 1;

Fig. 3 is a partial plan view, looking in the direction of the arrow 3 in Fig. 1;

Fig. 4 is an end elevation, partly in section and looking in the direction of the arrow 4 in Fig. 1;

Fig. 5 is a detail sectional view, taken along the line 5—5 in Fig. 3;

Fig. 6 is a detail sectional view, taken along the line 6—6 in Fig. 1, and

Fig. 7 is a detail side elevation, looking in the direction of the arrow 7 in Fig. 6.

Referring to the drawings, I have shown portions of an Axminster carpet loom including a loom frame 10 and a supplementary frame 11 for the needle motion. A drive shaft 12 extends longitudinally through the

frame 11 and is provided with a pin gear 14 cooperating with an intermittent gear or star wheel 15, mounted on a shaft 16 supported in fixed bearings 17 and 18. The pin gear 14 and star wheel 15 cooperate to form a so-called "Geneva" escapement and cause the shaft 16 to be alternately advanced and held at rest.

The gear 20 on the shaft 16 engages a pinion 21 on a shaft 22 supported in fixed bearings 23 and 24 (Fig. 3). The shaft 22 has a bevel gear 25 at one end thereof, meshing with a bevel pinion 26 on a cross shaft 27 rotatable in fixed bearings 28 and 29 and having a sprocket 30 secured thereon.

A chain 32 connects the sprocket 30 with a smaller sprocket 33 rotatable on a fixed stud 34 (Fig. 2). A pulley 36 is also rotatable on the stud 34 and is secured to the sprocket 33 to rotate therewith.

By the driving mechanism thus far described, the sprocket 33 and pulley 36 are given successive movements of angular rotation, which movements are intermittent but always in the same direction, which is anticlockwise as viewed in Fig. 1.

A channel iron or bar 40 is supported on brackets 41 and 42 (Fig. 1) above the frame 11 and is extended to the right in Fig. 1 beyond the bracket 42 to provide a support for a bracket 44. A short shaft 45 (Fig. 4) is mounted in a bearing 46 at the top of the bracket 44 and is provided at its rear end with a depending arm 48, in the lower end of which a stud 49 is secured. A take-up pulley 50 is mounted on the stud 49 and is loosely rotatable thereon.

A ratchet plate 52 (Figs. 1 and 4) is secured to the front end of the stud 45 and is provided with a horizontally extending arm 54 supporting a weight W. A weighted pawl 56 is mounted on a fixed pivot 57 and engages the teeth of the ratchet plate 52.

A driving band 60 is mounted on the pulleys 36 and 50 and is tensioned by the weight W, acting through the ratchet plate 52 and cross shaft 45. The band 60 is provided with spaced openings 62 and the pulley 36 is provided with tapered studs 64 adapted to pro-

ject through the openings 62 and thus form a positive driving connection with the band 60.

5 A block or bracket 66 (Figs. 6 and 7) is secured to the band 60 and provides a support for a cross-pin or stud 68 (Fig. 6). The stud 68 has a reduced bearing portion 70 on which one end of a connecting rod or link 72 is pivoted, and the stud 68 has a further reduced portion 74 which supports an anti-friction bearing for a roll 75.

10 The opposite end of the link 72 is pivotally connected to a block 80 (Fig. 2) slidable between dove-tailed guideways 81 on the fixed bar 40. The needle N is attached to the block 80.

15 It will be obvious that as the band 60 is intermittently advanced by the driving mechanism described, the block 80 will be caused to slide back and forth along its guideways 81 and will be brought to rest with a "sine-curve" or "connecting-rod" effect at each end of its path of travel.

20 As the force transmitted through the connecting rod 72 would tend to deflect the band 60 in its horizontal runs, I have provided angle bars 84 and 85 (Figs. 1 and 2) to support the roll 75 and to receive the thrust of the connecting rod. These bars 84 and 85 are 25 secured by braces 86 (Figs. 1 and 2) to the fixed horizontal bar 40.

25 Having described the details of construction of my improved needle mechanism, it will be seen that I have provided mechanism capable of reciprocating a needle smoothly and easily at desired intervals and at a higher speed than has been heretofore practicable, as all movements of the actuating mechanism are in the same direction, and as the reversal 30 of movement of the sliding block 80 and needle N is accomplished without shock and with all of the advantages of the usual "connecting-rod" or "sine-curve" motion.

35 Another advantage of my invention resides in the fact that the pins in the pin gear 14 may be irregularly spaced as desired so as to provide a short dwell of the needle when in the fabric and a longer dwell when the needle is out of the fabric, and furthermore to provide an exceptionally long dwell of the needle out of the fabric during the lowering of the yarn tubes and the insertion of the yarn tufts. By thus providing for a sufficiently long needle dwell on the tuft-inserting pick and for 40 shorter dwells on the other two picks, the speed of the loom may be substantially increased. In looms where the operation of the needle mechanism is identical for every pick, the loom is necessarily slowed down as the mechanism must operate on every pick at a speed slow enough to provide the necessary long dwell for the tuft-inserting pick.

45 Having thus described my invention and the advantages thereof, I do not wish to be limited to the details herein disclosed, other-

wise than as set forth in the claims, but what I claim is:—

1. Needle mechanism for an Axminster loom comprising a pair of spaced pulleys, a band mounted thereon, a driving shaft, a pin gear mounted on said shaft, a star wheel actuated thereby, a shaft for said star wheel, a positive driving connection by gearing, sprockets and chain between said star wheel shaft and one of said pulleys, means on said driven pulley to positively engage and drive said band, a device to which a needle may be attached, means to guide said device for straight line sliding movement, and a connecting rod pivoted to said device and connected to a portion of said band.

15 2. Needle mechanism for an Axminster loom comprising a pair of spaced pulleys, a band mounted thereon, a driving shaft, a pin gear mounted on said shaft, a star wheel actuated thereby, a direct driving connection from said star wheel to one of said pulleys whereby said star wheel and pulley always rotate in the same relative directions, means on said pulley to engage and drive said band, a slidable device to which a needle may be attached and means to connect said device to said band.

20 3. Needle mechanism for an Axminster loom comprising a device to which a needle may be attached, means to guide said device for sliding straight-line movement, a connecting rod pivoted to said device, a band supported for movement in a closed path alongside said guiding means, means to intermittently advance said band in a single direction only, a bearing member pivotally securing one end of said connecting rod to a point on said band, a roll on said bearing member, and fixed supports for said roll effective to prevent twisting displacement of the band by the connecting rod thrust.

25 4. Needle mechanism for an Axminster loom comprising a device to which a needle may be attached, means to guide said device for sliding straight line movement, a connecting rod pivoted to said device, a pair of pulleys spaced apart lengthwise of said guiding means, a continuous band mounted on said pulleys, a bearing member secured to said band and to which one end of said connecting rod is pivoted, means to advance said band intermittently in one direction only to effect reciprocation of said needle, and means to support said band in its straight runs against twisting displacement or displacement toward the center line of said pulleys by connecting rod thrust.

30 5. Needle mechanism for an Axminster loom comprising a device to which a needle may be attached, means to guide said device for sliding straight line movement, a connecting rod pivoted to said device, a pair of pulleys spaced apart lengthwise of said guiding means, a continuous band mounted on said

pulleys, a bearing member secured to said band and to which one end of said connecting rod is pivoted, means to advance said band intermittently in one direction only to effect
5 reciprocation of said needle, a roll for said bearing member and supporting bars mounted adjacent the straight runs of the band and effective to engage said roll and to support said band against twisting displacement or
10 displacement toward the center line of said pulleys by connecting rod thrust.

6. The combination in needle mechanism as set forth in claim 2, in which the pins in the pin gear are irregularly spaced circumferentially, whereby a different dwell of the
15 needle may be provided on different picks.

7. The combination in needle mechanism as set forth in claim 2, in which means is provided for varying the center line space between
20 the pulleys to take up slack in the band.

In testimony whereof I have hereunto affixed my signature.

WILLIAM W. ROBERTSON.
